MAXWELL C. ROSE, OF CLEVELAND, OHIO, ASSIGNOR TO THE CLEVELAND-AKRON
BAG CO., OF CLEVELAND, OHIO, A CORPORATION OF OHIO.

MACHINE FOR MAKING VALVED PAPER BAGS.

1,351,219.

Specification of Letters Patent. Patented Aug. 31, 1920.

Application filed July 14, 1919. Serial No. 310,611.

To all whom it may concern:

Be it known that I, MAXWELL C. ROSE, citizen of the United States, residing at Cleveland, in the county of Cuyahoga and 5 State of Ohio, have invented certain new and useful Improvements in Machines for Making Valved Paper Bags, of which the following is a specification.

This invention relates to a machine for 10 making valved paper bags, and the object of the invention is to provide co-acting mechanisms adapted to fold and close one end of a paper tube or bag, while tucking in one corner of the tubular bag to provide a 15 self-closing valve for the bag, all the parts of the machine co-operating and acting to feed, form and finish the bag step by step without cessation or interruption in the movement of the bag through the machine. 20 The paper bag or sack made by the present machine is designed to be relatively large and the stock from which it is made relatively tough and strong so that the bag or sack is adapted to withstand hard usage and 25 carry and hold a considerable amount of granular or powdered material. Further, the bag or sack is sealed and closed at both ends except at one corner where a simple fold provides a valved inlet through which 30 the material is fed or introduced until the bag is substantially full. When filled, the bag is inverted and the weight and pressure of the contents collapse and close the folded walls of the inlet opening at the corner of 35 the bag. The present machine takes a tube or bag in its flat state and by successive stages forms a corner valve and closes one end of the bag and discharges the completed bag in a flat state ready for filling operations. 40

In the drawings accompanying this application, Figure 1 is a top plan view showing the essential features of my invention and Fig. 2 is a side elevation thereof. Figs. 45 3 to 8, inclusive, are perspective views of the bag or sack in its various stages of formation from the time it enters the machine until completed and discharged.

The machine comprises a suitable base or 50 table 2, upon which the various operating parts are mounted. Thus, at the receiving end of the machine I show a series of conveying rollers 3 upon which a partly completed paper bag or sack S is laid and fed 55 with one longitudinal edge adapted to enter

between a pair of opposed endless belts or conveyers 4 and 5 respectively. These conveyers extend the length of the machine and are mounted or carried by suitable rollers or pulleys 6 supported on shaft 7. Power is 60 applied to one of these shafts by gears 8, and the coacting mechanisms hereinafter described are also driven through the same source of power transmitted to suitable drive shafts, gears, belts or chains. 65

The entry of bag S into the bite of the conveyers is temporarily checked by a stop plate 9 which is adapted to be raised and lowered by a cam 10 on the shaft 7 on the lower conveyer pulley at the receiving end 70 of the machine. The instant stop plate 9 is lowered the bag or sack S is fed forward and its open end or mouth passes beneath a hollow head 11 having a perforated inclined bottom 12 against which the top ply 75 of the open end of the bag is adapted to be drawn by vacuum or suction created within the head by a pump or fan connected to pipe 14. Thus, while the bag is moving forward the opposite plies at the open end of the bag are spread apart, especially at the advancing edge of the bag and at the corner so that a vertical wall 15 (Fig. 4) is formed at the corner directly in line with a rotating finger 16 which is driven by bevel gears 17 80 and belt 18 from motor M. As the bag moves forward the finger 16 is timed to strike wall 15 and tuck a triangular corner 19 of the bag between the upper and lower plies of the bag substantially as shown in Fig. 5, and before the finger has again completed a rotative movement the tucked bag has passed onward beneath a creasing disk 20 which is adapted to produce a crease on a straight line parallel with the end of the 85 bag across the corner folds and the two plies so that the end of the bag may thereafter be easily folded back and pasted flat upon the upper face of the bag. 90

However, before this final pasting operation occurs the two plies or sides of the bag must have paste applied upon the inside of the open ends so that this open end may be first pasted shut. This is accomplished immediately after the bag has passed creasing disk 20 during the interval of its passage beneath a second vacuum or suction head 21 which separates the plies at the open end of the bag as the bag travels forward so that an oscillatory finger or spout 110

- 22 may apply paste to the inside face on the bottom ply of the bag. Thus, as the bag advances and opens where tucked an entrance is afforded for the spout or finger 5 22 and the paste is conveyed from receptacle 23 through the hollow stem of the spout to the inner ply of the bag, and when the rear folded edge 24 of the bag engages the spout or finger 22 said finger or spout will turn 10 on its pivot or in its bearings under the tension of a spring 25 connected to an arm 26 on the spout, thereby permitting the bag to pass onward. As soon as the bag passes beyond this point the finger or spout is released and the spring carries the spout into 15 its original position to operate in the same manner on the next or succeeding bag.

Following this inner pasting operation the next step is to apply paste on the upper side of the bag between the creased line 20 and the outer end of the bag. This is accomplished by a paste wheel 27 located within and at the bottom of the paste receptacle 23 at the front of spout member 22 25 and this paste wheel 27 also serves to press the two plies together opposite the paste previously applied between the plies. Then as the bag advances, the end which has been creased and pasted enters a folding 30 device comprising an open-sided tube 28 having an enlarged flaring entrance and sloping walls terminating in a narrow elongated outlet, whereby the pasted end of the bag is curled upwardly and folded back 35 and down upon the top side of the bag the full width of the bag on the line of the crease made by creasing disk 20 so that the pasted portion will be folded upon itself and the straight end of the bag permanently 40 closed as this folded portion passes between a pair of presser rollers 34 before being discharged from the conveyer at the discharge end of the machine. The completed bag is discharged in a flat state, and is closed at 45 both ends except at one corner where the filling entrance and valvular folds are formed by the operations herein described.

The present disclosure represents a simple form of machine, whereby valved paper bags 50 may be produced in a continuous manner with exceptional economy in operation, but the details of construction of the machine may be considerably modified without departing from the spirit and scope of the 55 invention as hereinafter claimed.

What I claim is:

1. In a machine for making valved bags, means adapted to convey an open-ended tube in a given direction with its greater 60 length at right angles to the line of travel, means adapted to spread the plies of the tube apart at one corner and means to tuck said corner inwardly between the sides of the tube during a forward travel of the tube.

- 65 2. A machine for making paper bags, com-

prising means adapted to feed an open bag with one longitudinal edge in advance of the body of the bag, means adapted to tuck one corner of the open bag between the sides of the bag and means adapted to fold the 70 extremity of the bag where tucked upon the side of the bag.

3. In a machine for making paper bags, means adapted to feed a bag with one longitudinal edge in advance of the bag body, 75 means adapted to spread the sides of the bag apart at said advanced edge, and means adapted to tuck one spread corner of the bag inwardly between the sides of the bag.

4. In a machine for making paper bags, 80 means for conveying a bag with one end spread open and with one longitudinal edge in an advance position, means for tucking one corner of the bag where spread apart, and means for pasting and sealing the end of 85 the bag partially where tucked.

5. In a paper bag-making machine, means for feeding a flat bag or tube forwardly with one longitudinal edge in advance of the body, means for tucking the corner of the 90 advance edge of the bag or tube, means for creasing the bag or tube parallel to the end thereof, means adapted to apply paste between the creased folds of the bag or tube, and means adapted to press said pasted folds 95 together.

6. In a machine for making paper bags, means for feeding a flat elongated tube with one longitudinal edge disposed at right angles to the line of travel, means for tucking 10 one corner of the tube inward between the sides of the tube, means for creasing the tube transversely across one end thereof, means for applying paste between the creased portions of the tube, means for applying paste 10 upon the outside of the creased portion of the tube, and means for pressing the creased pasted portions of the tube together.

7. In a paper bag making machine, a set 11 of conveyers adapted to convey a tube edgewise between them, a rotatable tucking device adapted to tuck the sides of the tube at one edge and corner, a creasing device adapted to produce a crease transversely at its tucked end, and pasting and folding devices adapted to seal and close the creased portion of the tube.

8. In a machine for making paper bags, means adapted to convey a flat paper tube edgewise, a device adapted to spread the 12 sides of said tube apart at one end and corner, a device adapted to tuck a corner portion of the tube inwardly where spread apart, a device adapted to produce a crease transversely across said tube at its tucked 12 end, means adapted to spread the tucked tube apart temporarily, a device adapted to apply paste between the tucked creased sides of the tube, a device adapted to apply paste to the outer side and end of the tube where 13

creased, and a device adapted to fold the creased and pasted end portions of the tube back upon itself.

9. In a paper bag machine, a pair of conveyors adapted to feed a flat paper tube with a longitudinally folded edge in advance of the body of the tube, pneumatic means adapted to spread one end of the tube apart, a device adapted to tuck one corner of the tube inward between the sides of the tube, a member adapted to crease the tube transversely, pneumatic means adapted to open the creased or tucked portion of the tube, a pasting device adapted to project into the open end of the tube, a paste applying wheel

adapted to engage the top side of the end of the tube, and means adapted to fold and press the creased and pasted end of the tube shut.

10. In a paper bag machine, means for feeding a flat paper tube forwardly, a tucking device adapted to fold one corner of the tube inwardly, and an oscillatory paste applying device adapted to enter the tucked corner portion of said tube.

Signed at Cleveland, in the county of Cuyahoga, and State of Ohio, this 11th day of June, 1919.

MAXWELL C. ROSE.
